CLAIM

The ornamental design for a combined rechargeable dual function therapeutic massager and personal grooming device and recharging stand, as shown and described.

DESCRIPTION

FIGS. 1 through 7 generally describe the combined rechargeable dual function therapeutic massager and personal grooming device and its recharging stand.

FIG. 1 is a prospective view of a dual function therapeutic massager and personal grooming device and its recharging stand;

FIG. 2 is a front elevational view thereof;

FIG. 3 is rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Those portions of the recharging stand shown in broken lines in FIGS. 3, 6 and 7 form no part of the claimed design.
